US00D639733S

(12) **United States Design Patent**
Liu et al.

(10) **Patent No.:** US D639,733 S
(45) **Date of Patent:** ** Jun. 14, 2011

(54) **CHARGING DEVICE**

(75) Inventors: **Lin Liu**, Shenzhen (CN); **Kaihua Niu**, Shenzhen (CN); **Jianhua Zhang**, Shenzhen (CN)

(73) Assignee: **BYD Company Limited**, Shenzhen (CN)

(**) Term: **14 Years**

(21) Appl. No.: **29/381,539**

(22) Filed: **Dec. 20, 2010**

(30) **Foreign Application Priority Data**

Jul. 13, 2010 (CN) 2010 3 0239342

(51) **LOC (9) Cl.** 13-02

(52) **U.S. Cl.** D13/107

(58) **Field of Classification Search** D13/106–110, D13/118–119, 184, 199; D15/9; 320/103–105, 320/107–115

See application file for complete search history.
